[57] **ABSTRACT**

In a centrifugal pump in which the impeller and a first pole ring of a magnetic transmission form a unitary structure, the latter is driven through a magnetically permeable separating wall. The magnetic transmission has a second pole ring and, between it and the separating wall, a conductor pole ring comprising a plurality of conductors with the two pole rings being independently arranged for rotation with respect to one another. The two pole rings each have a plurality of pole faces of alternating polarity with one of the pole rings having more pole faces than the other, whereby rotation of one of the pole rings with respect to the other pole ring will be at a predetermined ratio.

CENTRIFUGAL PUMP WITH MAGNETIC DRIVE

RELATED APPLICATION

This application is a division of my copending application Ser. No. 9,916 filed Feb. 9, 1970 now U.S. Pat. No. 3,645,650.

BACKGROUND OF THE INVENTION

The invention relates to centrifugal pumps for liquids or gases, whose impeller forms a unit with a magnetic pole ring and which is driven by a rotating magnetic field, the rotating magnetic field being produced by a motor-driven pole ring having a number of poles which is greater than that of the said magnetic pole ring.

The invention thus relates to centrifugal pumps, whose impellers work at a speed different from that of the rotor of the driving motor. The transmission arrangement is not a magnetic coupling, but a magnetic transmission.

DESCRIPTION OF THE PRIOR ART

A magnetic transmission with three relatively coaxially arranged elements, at least two of which are rotatable independently of each other, is known. Two of these elements consist of rings, separated by an air gap, with non-meshing, magnetically conductive teeth, which form regions of alternately high and low magnetic reluctance, the difference between the number of teeth on the two rings being small, so that, on one diameter only, two teeth of the outer ring are positioned exactly opposite two teeth of the inner ring. One of these rings may be permanently magnetised or provided with a winding which magnetises the ring so that a magnetic field is produced which causes alignment of two oppositely positioned teeth of the rings. This transmission constitutes the magnetic analogue of the mechanical hypocycloid gear in which only two teeth of the outer ring mesh at any one time. Whereas extremely high stresses for power transmission can be employed with gears, only very small shear forces can be transmitted by magnetic transmissions with poles on either side of an air gap which enables contactless running. In consequence, only small torques can be transmitted by any known magnetic transmissions, so that they cannot be considered for the transmission of larger powers. Moreover, this kind of transmission is possible only for very high transmission ratios of, for example, 1:20 or 1:50 but not transmission ratios of 1:2 or 1:5, so that this kind of transmission does not present a usable substitute for gears for the transmission of larger powers.

A frictionless magnetic transmission is also known, in which ferro-magnetic coupling elements are separated by a predetermined distance from a driving and a driven part, the whole assembly being accommodated in a housing which provides a closed magnetic circuit. In this form of transmission, only one coupling element at a time carries the maximum magnetic flux, so that therefore only the principle of the stepping gear is applied, in which only a very small region of the circumference is actively employed for the transmission of torque at any one time. This magnetic transmission also has the disadvantages already mentioned.

Furthermore, a magnetic transmission is known, in which a driven magnetic system is coupled to a driving magnetic system by fields of magnetic force and the transmission ratio is formed by branching of the magnetic flux in a ferromagnetic coupling member. In a

simple construction the direction of rotation of the output of this transmission is not defined. Only by means of a plurality of systems which are angularly displaced and axially juxtaposed, can the direction of rotation of such transmissions be predetermined. The latter, however, has the disadvantage that the effective flux is at any one time confined to a region of not more than one-third of the axial length and that the magnetic paths become very large; for this reason again they are not suitable for the transmission of large powers.

By comparison, it is the purpose of the invention to provide centrifugal pumps having magnetic transmissions, capable of transmitting large mechanical powers with minimum material cost and any desired transmission ratio, and particularly at low transmission ratios.

GENERAL DESCRIPTION OF THE INVENTION

In a construction according to the invention, this is achieved by constructing the conductors in such a way that the magnetic flux flowing through a pole of the pole ring with the smaller number of poles is distributed over at least two poles of the pole ring with the greater number of poles. In a practical embodiment of this kind according to the invention at least one conductor has at least two pole faces facing the pole rings with the larger number of poles.

In another embodiment, the problem underlying the invention is solved by making at least one face of the conductor facing the pole ring with the larger number of poles at least as wide as the distance between two adjacent pole centres of this pole ring.

Preferably the three elements of a magnetic transmission according to the invention are arranged in the form of three concentric rings. If with this arrangement the number of the conductors equals twice the number of the poles of the inner pole ring which has the higher speed, then the alternating magnetic field which the driving pole ring produces in each conductor can be transformed into a two-phase, phase-symmetrical, circular and substantially sinusoidal rotating field, so that the same conditions apply to the driven pole ring as to the rotor of a three-phase induction motor.

The radial flux, which in an electric motor is provided by windings, is generated by permanent magnets of a rotating pole ring in these magnetic transmissions. By the use of high quality magnetic materials, the same induction as in the case of an electric motor can be provided, so that the transmittable torques correspond to those of electric motors having rotors of the same size. By contrast with simple motors, magnetic transmissions may also be built in synchronous form, if the driven pole ring is not in the form of an induction rotor (squirrel cage rotor) as in the case of an electric motor, but in the form of a permanent magnet rotor. This is not possible in the case of an electric motor, since the rotor would have to be accelerated to its full speed in one-fiftieth (or one-sixtieth) of a second, whereas the magnetic transmission is driven and therefore accelerated over a longer period at a lower angular acceleration.

By providing two permanent magnet pole rings for the input and output, all eddy current losses are eliminated; in the case of an electric motor, these usually account for more than 50 percent of all losses. The only source of losses left is the iron loss in the conductors, which however only amounts to a few watts per kilogram of iron. The efficiency of the new magnetic transmission, if both pole rings contain permanent magnets,

is therefore nearly unity, which is of decisive importance, having regard to the large power which are to be transmitted.

The main area of application of the centrifugal pumps having magnetic transmissions is the conversion of the speed of mains-fed induction motors whose maximum speed is limited. Since the output of centrifugal pumps for given dimensions of the casing increases as the speed, a step-up transmission results in space- and material saving constructions. Basically, however, the invention may also find application for centrifugal pumps whose impeller speed is less than that of the motor, particularly in the case of driving- or medium frequency motors.

If the number of conductors is three times that of the poles of the high speed pole ring with the smaller number of poles, it is also possible to produce a three-phase circular rotating field, which however is of advantage only where the degree of lack of uniformity of rotation which is dependent on the number of poles could be objectionable.

It is emphasised that in a centrifugal pump having a magnetic transmission according to the invention, any one of the three elements can be the driving and any one of the three elements the driven element. It is further emphasised that one of the three elements must be held stationary or supported by a stationary system, which is usually done by supporting it by a housing element.

Transmissions for centrifugal pumps according to the invention may be built up in the form of a cylinder, superimposed by a hollow cylinder and a further hollow cylinder surrounding them. The inner and outer pole rings may also be arranged relatively eccentrically. The air gaps need, however, not necessarily lie on cylindrical envelopes; they may also lie on conical envelopes, spherical surfaces and planes. In the latter version the arrangement consists of three discs, and it is not necessary for the rotating discs to be geometrically co-axial.

In the case of high-speed centrifugal pumps, which require a high driving speed, the high-speed pole ring of the magnetic transmission is constructed as a unit with the impeller wheel, whilst the low-speed pole ring is driven by the motor. The third element, the conductor ring, is separated from the pump impeller by a wall, so that hermetic sealing is effected. Hermetically sealed pumps with thin-walled magnetically permeable separating walls are known. The invention enables the construction of pumps in which the walls through which magnetic forces are fed into the interior of the pump, can be made of any desired thickness, so that hermetically sealed pumps constructed with magnetic transmissions in accordance with the invention can be manufactured for pressures which can be practically as high as desired and at which thin-walled magnetically permeable separating walls of magnetic couplings would tear. In such constructions, the thin-walled separating wall only acts as a sealing element, whilst the conductor ring also acts as a mechanical support against high pressures. For such pumps also magnetic transmissions with a transmission ratio $m = 1$ are meaningful.

Since the torque is transmitted by a rotating magnetic field, the new magnetic transmissions can also be combined with magnetic bearing systems, so that besides contactless transmission of the torque, the bearing can also be contactless, except for a support at the centre of a spherical section.

The magnetic transmissions for centrifugal pumps in accordance with the invention may be classified according to their geometric parameters; these include the number of poles of the low speed and high speed pole ring, the number of conductors, the number of pole areas of the conductors, as well as the spacing of the pole areas of adjacent conductors. Accordingly, let, by definition:

p = Number of poles of the low speed pole ring (large number of poles)

q = Number of poles of the high speed pole ring (small number of poles)

m = Transmission ratio of the transmission, where m always = p/q

r = Number of conductors

r_p = Number of pole areas of the conductors facing the low speed pole ring

r_q = Number of pole areas of the conductors facing the high speed pole ring

j = Spacing of the pole centres of the pole areas facing the low speed pole ring, of different adjacent conductors, relative to the spacing of the centres of adjacent poles of the low speed pole ring.

The highest transmission ratio is always given by the ratio

$$m = (p/q)$$

In this case the conductor ring formed by conductors 17 is held stationary. If, instead of the conductor ring, the low speed pole ring is held stationary, then, for the same embodiment, we get the lower transmission ratio of the conductor ring to the high speed pole ring

$$m_1 = -(m - 1)$$

Using the same transmission, we get the lowest transmission ratio when the high speed pole ring is held stationary. We then get between the low speed pole ring 11 and the conductor ring, the transmission ratio

$$m_2 = (m/m - 1).$$

All the transmissions for centrifugal pumps in accordance with the invention thus enable three transmission ratios to be obtained, the direction of rotation for the transmission ratio m changing in the case of the ratio

m_1 . These speed ratios are exactly true only where two pole rings are magnetised by permanent- or electromagnets. If one of the pole rings is in the form of a hysteresis magnet or a short-circuited rotor like the rotor of an electric motor, then the slip of such a pole ring is superimposed on the transmission ratio. In these magnetic transmissions it is not necessary for the driving portion to be provided with permanent- or electromagnets. It is also permissible for the driven pole ring only to effect the magnetisation. According to a preferred feature of the invention, a claw pole construction is provided for the magnetic material, in which adjacent poles of the same polarity are short-circuited together by soft magnet rings, so that a large portion of the entire magnetic material is operative at all times.

The particular provision and construction of the conductors which conduct the magnetic flux between the pole rings in accordance with the invention results in the magnetically active material of the pole ring with the greater number of poles being almost completely utilised and thereby the torque transmitted by the transmission being considerably increased compared with known magnetic transmissions, in which only a

portion of the magnetically active mass corresponding to the transmission ratio contributes to the torque transmission at any one time.

BRIEF DESCRIPTION OF THE DRAWINGS

Some advantageous embodiments of the invention will now be described with reference to the drawings.

FIG. 1 shows a pump with a magnetic transmission;

FIG. 2 shows a turbo-compressor drive with a magnetic transmission;

FIG. 3 shows a borehole pump with a step-up magnetic transmission;

FIG. 4 shows an axial-flow pump with a step-down magnetic transmission;

FIGS. 5a-5d are a plan view of a preferred form of a magnetic transmission constructed according to the invention with odd series cascading in one direction and having transmission ratios 5, 9, 13 and 5 respectively;

FIGS. 6a-6c show a different embodiment of a magnetic transmission with odd series cascading in the opposite direction of rotation than in FIG. 5 and having the transmission ratios 3, 7, 11 respectively;

FIGS. 7a-7d show a further embodiment of a magnetic transmission with even series cascading in one direction having transmission ratios 2, 4, 8 and 6 respectively;

FIGS. 8a-8d show a magnetic transmission having even series cascading in a direction opposite to the direction of rotation of FIG. 7 and having transmission ratios 4, 6, 8 and 10 respectively;

FIG. 9 shows a spherical construction of the magnetic transmission according to the invention, preferably for pumps with magnetic bearings;

FIG. 10 shows a developed view of a sheet metal strip for producing the conductors.

FIG. 11a is a plan view of a part of a low speed pole ring for use in a magnetic transmission where the ring has magnetically conductive pole shoes;

FIG. 11b is an enlarged section through a part of a different embodiment of a low speed pole ring; and

FIG. 11c is a section through a still further embodiment of a low speed pole ring having claw poles;

FIG. 12a is a plan view of a magnetic transmission similar to that shown in FIG. 5b illustrating the magnetic lines of flux in one position of the high speed pole ring;

FIG. 12b is a view similar to FIG. 12a illustrating the magnetic lines of flux in a different position of the high speed pole ring; and

FIG. 12c is a view similar to FIG. 12a illustrating the high speed pole ring in a still further position.

FIG. 13a illustrates the construction of a magnetic transmission having the ratio 1 to 1 wherein the conductors are arranged radially;

FIG. 13b is a view similar to FIG. 13a but where the conductors are arranged in a cross formation and where the direction of the rotation of the pole ring is opposite to that shown in FIG. 13a;

FIG. 14a is a plan view of a magnetic transmission with a three-phase rotating field;

FIG. 14b is a view similar to FIG. 14a having different conductor configurations;

FIG. 14c is a view similar to FIG. 14a having a different number of conductors; and

FIG. 14d is a view similar to FIG. 14a of a still further embodiment having a different number of conductors and conductor configurations;

FIG. 15 shows a short-circuited rotor in a magnetic transmission with a conductor ring of special construction.

DESCRIPTION OF THE PREFERRED EMBODIMENTS

10 FIG. 1 shows a pump according to the invention with a magnetic transmission for increasing the speed of the pump runner 123, whereby the pump may be constructed in a very compact manner. The conductors 17 are made up of foils arranged one above the other; the pole ring 120 consists of radially magnetised permanent magnets which are joined to each other in magnetically conducting manner by the ring 121 for closing the magnetic circuit. The pole ring 122 drives the pump runner 123. A magnetically permeable separating wall 124, of spherical form, is provided for hermetically sealing the interior of the pump. The motor 125 drives the outer pole ring via the disc-like wheel 126.

20 FIG. 2 shows a turbo-machine of the same kind as that of FIG. 1, but designed as a compressor, particularly for refrigerants. In these compressors, hermetic sealing is of very great importance, since refrigerant is always lost through the shaft seals. Since compressors run at appreciably higher speeds than pumps, the invention provides for the conductors 130 a construction of extremely thin laminae with minimum hysteresis and eddy current losses, such as those used in audio frequency transformers. Pole shoes 132 of soft magnetic material are provided between the permanent magnet pieces 131. of the outer pole ring and the conductors 35 130. The spherical separator 134 is preferably made of synthetic material, e.g. a glass fibre reinforced epoxy resin, which is made impereable to gasses by a very thin layer of metal by electro- or vapour deposition.

30 FIG. 3 shows a bore hole pump, in which a motor 111, which is accommodated in a hermetically sealed housing 110, drives the pole ring 112 of the magnetic transmission with the conductor ring 113. The high speed pole ring 115 rotates in a conical, magnetically impermeable, separating wall 114, the pole ring being 40 conical and provided with helical channels 116, which convey a small quantity of liquid into the magnetic "air gap." This results in hydrodynamic lubrication, so that further bearings can be dispensed with.

45 Water is admitted through the orifices 118. The cap 119, which also rotates, prevents the ingress of sand into the space formed by the separating wall. Since the velocity pressure of the pump varies with the square of the speed, a pump runner 117 in a construction according to the invention with a transmission ratio of 3 : 1 takes the place of a total of nine conventional runners, with the result that the pump is considerably simplified.

50 FIG. 4 shows a stirring mechanism in the form of an axial-flow pump which is driven by a step-down magnetic transmission in accordance with the invention. The inner, high speed pole ring 102 is mounted on the motor shaft 101 of the motor (shown broken); the conductor ring is made up of laminar conductors 103 and, with its rotating field, drives the low speed outer pole ring 106 with the stirrer 105, whose hub is supported 55 on a spherical bearing 107. A conical sheath 108 serves to support the spherical bearings, the sheath being hermetically sealingly joined to the separating membrane

109, which envelopes the conductors 103 and seals the motor against the liquid space of the stirring mechanism.

FIGS. 5a - 5d show forms of the magnetic transmission according to the invention, to which the mathematical law

$$m = 4k + 1$$

applies, where k is zero or any desired natural number. Moreover, for all the transmissions shown in this figure

$$r = 4 \text{ and}$$

$$j = 0.5$$

were chosen.

Then we get for

$$\text{FIG. 5a with } k = 1 \text{ } m = 5$$

$$\text{FIG. 5b with } k = 2 \text{ } m = 9$$

$$\text{FIG. 5c with } k = 3 \text{ } m = 13$$

Reference numeral 11 designates the low speed pole ring with the salient north poles 12, which, in FIGS. 5a,b,c are m in number, and the salient south poles 13 which, in FIGS. 5a,b,c are also m in number. Reference numeral 14 designates, in FIGS. 5a - d, the high speed pole ring, the reference numeral 15 in each case designating the north pole and 16 the south pole.

In FIGS. 5a - 5c

$$q = 2$$

was selected, i.e. the lowest possible value.

Then, in accordance with the invention, the number of conductors 17 is preferably twice this value, viz. 4.

In the embodiments shown in FIGS. 5a - 5d each individual conductor has a plurality of pole faces facing the outer pole ring, i.e. in the forms according to FIGS. 5a and 5d, 2 each, in the form according to FIG. 5b there are 3, and in the form 5c there are 4.

For the examples in which the transmission ratio

$$m = 5,$$

FIG. 5d shows an arrangement which, compared with FIG. 5a, is characterised by twice the number of elements 12, 13, 15, 16, 17, the transmission ratio m being the same.

In accordance with the invention, any desired integral multiple can be selected instead of the doubling described. It will be seen that the four-pole arrangement of FIG. 5d has arisen from developing the circumference of FIG. 5a twice, so that the same laws must apply to the aforesaid multiples, as to the simplest arrangement, i.e. the two-pole arrangement, whose operation will be described in greater detail with reference to FIG. 12.

FIGS. 6a - 6c show other preferred arrangements of the magnetic transmission according to the invention, which follow the mathematical law

$$m = -(4k - 1),$$

where k is any desired natural number, but not zero.

Furthermore, in this figure,

$$r = 4$$

and

$$j = 1.5$$

were selected for all the transmissions shown.

Then we get for

$$\text{FIG. 6a with } k = 1 \text{ } m = -3$$

$$\text{FIG. 6b with } k = 2 \text{ } m = -7$$

$$\text{FIG. 6c with } k = 3 \text{ } m = -11.$$

In FIGS. 6a - 6c the same reference numerals are used for parts performing the same functions, as in FIGS. 5a - 5d.

FIGS. 7a - 7d show further preferred forms of the magnetic transmission according to the invention, which follow the mathematical law

$$m = 2(k + 1),$$

15 where k is zero or any desired natural number. Furthermore, in these figures,

$$r = 4$$

and

$$j_1 = 0.5 \text{ and } j_2 = 2.5$$

were chosen.

As per the definition, by j_1 is to be understood the smallest ratio j which occurs three times per magnetic 25 transmission, and by j_2 the largest ratio j which occurs once per magnetic transmission, of this group of magnetic transmissions characterised by the above formula, which is characterised by the number of conductors

$$r = 4.$$

Then we get for

$$\text{FIG. 7a with } k = 0 \text{ } m = 2$$

$$\text{FIG. 7b with } k = 1 \text{ } m = 4$$

$$\text{FIG. 7c with } k = 2 \text{ } m = 6$$

$$\text{FIG. 7d with } k = 3 \text{ } m = 8.$$

In FIGS. 7a - 7d the same reference numerals are used for parts performing the same functions, as in 40 FIGS. 5a - 5d.

FIGS. 8a - 8d show further preferred forms of the magnetic transmission according to the invention, which follow the mathematical law

$$m = -2(k + 1),$$

45 where k is any desired natural number, but not zero.

Furthermore, in these figures,

$$r = 4$$

50 and

$$j_1 = 1.5 \text{ and } j_2 = 3.5$$

were chosen.

Then we get for

$$\text{FIG. 8a with } k = 1 \text{ } m = -4$$

$$\text{FIG. 8b with } k = 2 \text{ } m = -6$$

$$\text{FIG. 8c with } k = 3 \text{ } m = -8$$

$$\text{FIG. 8d with } k = 4 \text{ } m = -10.$$

In FIGS. 8a - 8d the same reference numerals are used for parts performing the same functions, as in FIGS. 5a - 5d.

65 The number of pole faces of each conductor, which in accordance with the invention produces the outstanding results, depends entirely on the number of these conductors used and the number k . Thus in the

forms 5a - 5d, in which k may be zero or a natural number, the number of the pole faces on a conductor, which face the pole ring with the larger number of poles is

$$r'_p = (r/4)(k+1),$$

whilst in the form according to FIGS. 6a to 6c, in which k is a natural number,

$$r'_p = (r/4)k.$$

For the forms shown in the FIGS. 7a to 7d, the sum of the pole faces is given by

$$r_p = m - 2$$

whilst for the forms shown in the FIGS. 8a to 8d

$$r_p = m$$

applies;

In these expressions $r'_p = r_p/r$ and

$$r'_{p1} = r_p/r \text{ and } r'_{p2} = r_p/r + 1,$$

where the division r_p/r leaves a remainder.

FIG. 9 shows a magnetic transmission in longitudinal section, in which the low speed pole ring consists of a ring magnet 51 and soft magnetic inserts 52 affixed thereto by adhesive, whose number corresponds to the number of poles of the magnet. They produce a periodic change of polarity in the stationary conductors 53.

This acts on the high speed pole ring 54 which has the smaller number of poles and consists of a shaped magnetic part. In the present case, a spherical separator 55, preferably of non-magnetic material of low electrical conductivity, is arranged between the conductors 53 and the high speed pole ring 54, whilst the high speed pole ring 54 forms a unit with a pump impeller 56. At the nadir of the separator, a column 57 is provided which terminates in a sphere and supports the pump impeller 56 at 58 in the centre of the separator 55. The centres of the magnetic poles of the conductors 53 as well as those of the pole ring 54 are located at the point of intersection of a cone 59 with the concave and convex areas respectively forming the boundaries of the air gap, whereby a magnetic bearing is provided for the pump impeller 56. The member 60 is an iron ring which increases the magnetic flux.

FIG. 10 is a developed view of a metal strip, which produces a spiral body 53 in accordance with FIG. 9 when the strip is wound up. The poles 63 occupy only a portion of the circumferential region of the poles 64. The connecting bridges 65 and 66 between the conductors 17 and 17' are so narrow that they provide adequate mechanical strength but present no significant magnetic short-circuit.

FIG. 11a shows a plan view of a form of the low speed pole ring, oxide magnets 70 being provided between soft iron angles 71. By this means it is possible to obtain greater flux density towards the air gap than can otherwise be achieved by means of sintered magnets.

FIG. 11b shows a section through an externally rotating pole ring, which consists of a permanent magnet ring 73, magnetised axially, and two symmetrically arranged shaped soft iron parts 74 and 74'. The soft iron parts consist of connecting rings 75 and claw poles 76 which are preferably tapered. The fewer of the poles 76 are operative at any one time, the larger must be the cross-section of the circuit closing rings 75, so that the

entire circumferential range of the magnet 73 is utilised.

FIG. 11c shows a similar construction of a ring with claw poles, in which again a plurality of axially magnetised magnet rings 73' are arranged between claw pole rings 74'. The adjacent claw poles 76' form a north pole and the adjacent claw poles 77 form a south pole. This arrangement makes possible the use of materials of extremely high coercive force, particularly Samarium-or Cerium based materials, which require the use of magnets extending over an extremely small range in the direction of magnetisation.

The transmissions in accordance with the invention, which have been particularly described with reference to FIGS. 5 - 9 are constructed in the form of two-phase, circular or elliptical rotating field systems, in which the four conductors 17 each produce two alternating fields, relatively displaced in time by $\pi/2$, when one of the two pole rings is moved relative to the conductor ring.

FIGS. 12a - c show details of the magnetic flux for three particular positions of the two pole rings, which in this case are movable, relative to the fixed conductor ring which consists of the totality of the conductors 17.

FIG. 12a shows the high speed pole ring 14 in a horizontal position with its north pole 15 on the left; the lines of force from it traverse the conductor 17a, returning to the south pole 16 of the inner pole ring, via three south poles 13, the middle one of which is marked with an x, and the ferro-magnetic envelope of the pole ring 11 as well as its north pole 12 and the conductor 17b. The relative position of the pole rings which is fixed in this way, is stable.

If now, as is shown in FIG. 12b, the pole ring 11 is moved clockwise by half a width of its pole face, then the magnetic flux branches into the conductors 17a/17b and 17a' and 17b'; in this way the pole ring 14 is subjected to a force which also tends to turn it clockwise. The two pole rings 11 and 14 reach their next stable position in the position shown in FIG. 12c; the high speed pole ring 14 will then have traversed an angle which is larger by the factor $m = 9$ than the low speed pole ring 11.

The movements described are determined by the position of the pole faces 21 of the conductors 17 which face the low speed pole ring and the position of the pole faces 22 of the conductors which face the high speed pole ring. The pole faces 21 of one and the same conductor always each connect poles of the same polarity with each other; their angular spacing is thus determined by the angular spacing 27 of the centres 25 and 25' of adjacent poles of the low speed pole ring 11. Apart from the ratio of numbers of poles of the two pole rings 11 and 14, the angular spacing 24 of the centres 23 and 23' of adjacent conductors 17 and 17' primarily determines the transmission ratio and direction of rotation of the transmission. In the preferred embodiments described with reference to FIGS. 5a and 8d it was also shown that this angular spacing mathematically defines the laws governing entire groups of transmissions.

In the foregoing description of the movements which take place, it was assumed that the conductor ring is kept stationary. However, if instead the low speed pole ring 11 with the larger number of poles is kept stationary, then in all cases we get a transmission ratio

$$m_1 = -(m-1).$$

Finally, if the high speed pole ring 14 with the smaller number of poles is kept stationary, then we get between the conductor ring and the low speed pole ring a transmission ratio

$$m_2 = (m_1/m - 1).$$

Thus all the magnetic transmissions make it possible, in principle, to provide three different transmission ratios by means of a single transmission unit, by selecting one of the elements 11, 14 or 17 for coupling to the stationary housing. This advantage can be made use of in full measure by the co-axial construction of the magnetic transmissions described, in accordance with the invention.

The two magnetic transmissions shown in FIGS. 13a and 13b are characterised by the special case of the value of

$m = 1$, which is of importance in the case of pumps for high system pressures.

In the examples drawn, a four-pole form of construction has been chosen but this is not significant in principle.

These transmissions have the principle of the two-phase rotating field construction in common with the examples shown in FIGS. 5a - 8d, but do not constitute typical representatives of larger groups of transmissions.

In both cases, the parameters referred to above as characteristics, have the following values:

$$p = q = 8$$

$$r = r_p = r_q = 16$$

The difference between FIGS. 13a and 13b resides in the fact that in the first case the conductors 17 are arranged radially whereas in the second case the conductors 17a and 17a' are arranged in a relatively crossed formation, and likewise the conductors 17b and 17b', so that, in accordance with the manner of operation explained with reference to FIG. 12, the direction of rotation of the pole ring 14 in FIG. 1b is opposite to that in FIG. 1a.

FIGS. 14a - 14d show further possible forms of construction of magnetic transmissions according to the invention; from each of the forms shown, a series of them can again be deduced. However, since these do not find much application, this has not been done.

FIG. 14a shows a magnetic transmission with a three-phase rotating field. When the conductor 17' is in full alignment with the north pole 12', the conductor 17'' is still only in partial alignment with the north pole 12'', so that the flux density in this pole is lower. There is no flux density yet in the conductor 17''. Its flux density increases at the same rate as that at which the flux density in the conductor 17' decreases.

FIG. 14b shows the same kind of construction, in which the conductors 17' and 17'' are practically identical to the conductors in FIG. 14a whilst the conductor 17'' offers twice the pole width to the low speed pole ring. The conductor 17'' serves the purpose of increasing the flux, since the north pole 12' is positioned opposite the pole 17'' for as long as the two conductors 17' and 17''' are successively so positioned.

FIG. 14c shows a construction with 4 conductors, three conductors 17, 17', 17'' of which are at any one

time positioned opposite a pole of the low speed pole ring, whereas the fourth conductor 17''' is at any one time positioned opposite two poles of the same polarity of the low speed pole ring, whereby the air gap flux density is reduced; this leads to less leakage and a greater factor of utilisation.

FIG. 14d shows an arrangement for the transmission ratio $m = 2 : 3$. The four-pole high speed pole ring 14 receives, via the conductors, a non-uniform rotating field which is produced by the six poles of the low speed pole ring 11. The conductors 17 and 17' produce a two-phase rotating field in the opposite direction, whilst the remaining conductors serve the purpose of closing the magnetic circuit and only offer alternating magnetic fields for torque production. The degree of non-uniformity, which is substantial with this form of construction in particular, can be put to advantage in mixing and emulsifying devices. If a high degree of uniformity is desired, this can in all cases be accomplished by a helical arrangement of poles and conductors in the manner known in relation to the armatures of electric motors.

FIG. 15 shows a short-circuited rotor 90 with the squirrel cage winding, in section, only one half, symmetrical about the axis of rotation 92, being shown. The outer pole ring consists of two concave rotational bodies 93 and 93' of permanent magnet material, which are held in an iron ring 94 for completing the magnetic circuit. The stationary soft iron pole 95 is of inwardly converging construction, so that the flux density which in the air gap 96 is limited by the quality of the magnets, is increased in the air gap 97.

I claim:

1. A centrifugal pump for liquids and gases, having a pump chamber and an impeller, a first magnetic pole ring forming a unit with said impeller, a magnetically permeable separating wall which defines the wall of said pump chamber in the region of said first pole ring, and an arrangement for producing a rotating magnetic field for driving said first pole ring, wherein the improvement comprises providing a second pole ring (17) and a third pole ring (120) outside said pump chamber, said second pole ring (17) being separated from said first pole ring (122) by a first magnetic air gap and from said third pole ring (120) by a second magnetic air gap, and a motor driving one of said second pole ring (17) and said third pole ring (120), and said first pole ring (122) comprising magnets.

2. A centrifugal pump according to claim 1, wherein said first pole ring is constructed as a segment of a sphere and said second pole ring as a hollow sphere.

3. A centrifugal pump according to claim 1, wherein said first pole ring (115) has spiral grooves (116).

4. A centrifugal pump according to claim 1, including a housing for said pump and said motor and wherein said motor and said third pole ring are hermetically separated from said pump chamber in said housing by said separating wall.

5. A centrifugal pump according to claim 1, wherein said pump impeller (117) is connected to said pole ring (115) with its inlet side facing the latter.

6. A centrifugal pump according to claim 1, wherein said second pole ring is built up from a sheet metal spiral.

7. A centrifugal pump according to claim 1, wherein said third pole ring (120) defines a hollow cylinder and drives said first pole ring (122) via said second pole

ring (17), the latter being assembled from sheet metal discs.

8. A centrifugal pump according to claim 1, wherein said first pole ring rotates at a higher speed than said third pole ring and the volume of magnetic material of said third pole ring (120) is several times as great as the volume of the magnetic material (122) of said first pole ring.

9. A centrifugal pump according to claim 1, wherein said spherical separating element (134) consists of non-metallic material.

10. A centrifugal pump according to claim 1, wherein said second pole ring is constructed in the form of a pressure cylinder.

11. A centrifugal pump according to claim 1, wherein said first pole ring and said third pole ring have the same number of poles.

12. A centrifugal pump according to claim 1, wherein said first pole ring is of spherical construction and forms a unit with said impeller said second pole ring defines a conductor ring the centres of the magnetic poles of said first pole ring and of said conductor ring are arranged on the surface of a sphere and said impeller is axially supported at its centre.

13. A centrifugal pump according to claim 12, wherein said second pole ring (130) is disposed between two concentric spherical shells.
